UNITED STATES PATENT OFFICE.

LEVI TEEGARDEN, OF KNAPP, WISCONSIN.

STAKE-HOLDER.

1,075,448.

Specification of Letters Patent.

Patented Oct. 14, 1913.

Application filed April 18, 1911. Serial No. 622,013.

To all whom it may concern:

Be it known that I, LEVI TEEGARDEN, a citizen of the United States, residing at Knapp, in the county of Dunn and State of Wisconsin, have invented a new and useful Improvement in Stake-Holders, of which the following is a specification.

This invention relates to a device for securing log holding stakes in position, and for permitting certain of the stakes to drop when the logs are to be unloaded.

The object of the invention is to insure the safety of the workmen engaged in unloading logs, also to prevent accidental falling of any of the logs from the car upon the main track while said car is standing upon a siding, or to prevent the dropping of any of the logs at any time through carelessness in handling the car.

20 A still further object of the invention is to release both ends of the log at the same time and to thereby prevent the logs falling cross-wise, as is the case where the stakes holding the logs upon the car are removed one at a time.

25 The invention in brief consists of a stake holder having a movable bottom and side, means for normally holding said side and bottom into proper position with relation to fixed sides so as to form a pocket within which the lower portion of the stake is secured, the said movable bottom and side falling downwardly when released, and thereby releasing the stakes upon one side of the car and permitting the logs to roll from the car upon the usual skid.

30 In the accompanying drawing: Figure 1 is a plan view of a car provided with two sets of stake holders upon each side, one set 40 of stake holders having stakes therein, and the other set showing the stakes removed upon one side. Fig. 2 is a section on the line 2—2 of Fig. 1 a plate being removed. Fig. 3 is a detail perspective view showing 45 one of the stake pockets.

35 In these drawings 1 represents an ordinary log car, which is of sufficient length to receive two piles of logs and which is therefore provided with two sets of stake 50 holders 2, of the ordinary construction upon one side of the car, and in which are secured suitable stakes 3. Upon the opposite side of the car are placed my special stake holder

which consists of two vertically arranged parallel plates 4, which plates are bolted 55 to opposite sides of the end portions of transverse beams 5, the plates extending outwardly upon the sides of the car beyond the beam. Pivotal connected to and between said side plates is a curved or angled plate 60 6 which forms the bottom and outer side of the stake pocket. Shafts 7 pass transversely through the plates 4 and the beams and suitable chains 8 are secured to eyes 9, carried by the free ends of the plates and 65 are also secured to and adapted to be wound upon the shaft 7. It will be understood of course that a shaft is provided for each set of pockets so that each pile of logs can be handled independent of the other. Operating 70 shafts 10 are journaled across the car and are provided upon one end with worm gears 11 which mesh with worm wheels 12 carried by the shaft 7, and at the opposite ends the shafts 10 are provided with hand 75 wheels 13 which may be locked against rotation by any suitable means, such as a chain, and a seal as at 14, or by means of a chain and pad lock. The stakes 3 which are placed 80 in the special form of pockets are connected 80 to the stakes 3 fitting in the regular pockets by means of the usual top chains 15.

When the logs in a pile are to be unloaded it is simply necessary to disengage the top chains connecting the stakes upon opposite 85 sides of the pile of logs, and then by rotating the proper hand wheel 13 one of the shaft wheels 7 will be rotated so as to unwind the chains 8, thereby permitting the plates 6 forming portions of the pockets of the stakes 90 to be dropped to fall into the position shown in dotted lines in Fig. 2 and in full lines in Fig. 3. The pressure of the logs upon the stakes will of course force them from the pockets and the logs permitted to roll upon 95 the usual receiving skids. It will be obvious of course that if desired my pockets can be arranged upon both sides of the car by duplicating the construction shown in order to discharge logs from either side. It will also 100 be obvious that a workman operating the hand wheel for the purpose of releasing two of the stakes is upon the opposite side of the car from that upon which the logs will be discharged and is therefore out of danger of 105 injury from the falling of the logs.

What I claim is:—

The combination with a car having trans-
verse beams, of plates carried by and pro-
jecting beyond said beams, a movable bot-
tom and side member pivotally mounted to
swing between each pair of plates, a shaft
passing through said plates and beams, and

chains pivotally connected to said movable
bottom and side member and adapted to
wind on said shaft adjacent said beams.

LEVI TEEGARDEN.
